Patented Apr. 25, 1922.

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

REGULATING VALVE FOR ROCK DRILLS.

1,414,222.

Specification of Letters Patent. Patented Apr. 25, 1922.

Application filed July 6, 1920. Serial No. 394,227.

To all whom it may concern:

Be it known that I, FRED M. SLATER, a citizen of the United States, residing at Easton, in the county of Northampton, State of Pennsylvania, have invented a certain new and useful Improvement in Regulating Valves for Rock Drills, of which the following is a specification.

This invention relates to valves for regulating the fluid actuated rotating motor of a rock drill in order to maintain substantially constant speed of rotation of the drill steel under varying conditions of load and air pressure.

15 The primary object of the invention is to secure a simple and reliable valve mechanism which will automatically regulate the supply of motive fluid to the rotation motor as the drill steel encounters varying resistance to rotation in drilling.

Another object of the invention is to enable a main valve to be automatically controlled by means of an auxiliary pilot valve which is subject to a varying pressure with 25 in the intake side of the motor casing in accordance with the conditions of the work.

Further objects of the invention will hereinafter appear and to all of these ends the invention consists of the devices and features of construction substantially as hereinafter fully described and claimed in this specification and shown in the accompanying drawings in which,

Figure 1 is a top plan view partly in longitudinal section of so much of a rock drill as will illustrate the invention,

Figure 2 is a longitudinal side elevation of the machine with certain parts in vertical section,

40 Figure 3 is an enlarged transverse sectional view of the rotating motor and automatic valve mechanism shown diagrammatically.

Referring to the drawings the cylinder A 45 of any suitable or usual form is provided with the usual front head B having the rotation sleeve C through which the drill steel D extends to receive the impact blow of the piston hammer E. The front head B is connected to the cylinder A as by means of spring pressed side bolts F. Any suitable rotation motor may be provided operatively connected to rotate the drill steel D, in this instance a gear motor being shown 55 within the back end portion G of the ma-

chine, comprising the gears H and J one of which as the gear J is keyed to a counter-shaft K at one end, the other end of the shaft having a pinion L meshing with a gear O having a pinion P meshing with the 60 gear Q on the rotation sleeve C.

The gears H and J of the rotation motor are preferably provided with suitable roller bearings one of which is shown at R and the shaft K has a roller bearing S at its forward end. The shaft K preferably passes through the chamber T in the walls of the cylinder A which forms an exhaust chamber for the rotation motor. The chamber is vented to atmosphere through the openings 70 U which muffles or silences the noise produced when air passes through motors of this type.

The back end portion G of the drill cylinder forming the motor casing is closed by a 75 suitable back head V having the motive fluid supply inlet W, the water cap X and the automatic motor controlling valve mechanism. Motive fluid enters the machine at the inlet W and passes to the bore Y of the 80 cylinder A and also passes through the supply port Z to the motor. The exhaust from the motor passes out through the exhaust port a to the exhaust chamber T and thence to the atmosphere.

Within the back head V is provided a main valve b having a pressure surface represented by the front end c constantly subjected to the pressure of the incoming motive fluid tending to close the valve. The 90 end c is preferably somewhat smaller in diameter than the port d so that the port d is never fully closed but a throttling effect is secured due to the tapered neck e of the valve.

The main valve b is preferably provided with a tubular barrel f within which a spring g is compressed tending to open the valve. A rear pressure surface of the main valve, or rear pressure surfaces represented 100 by the rear end of the valve and the interior surfaces are subjected to the varying pressure due to a relatively small amount of fluid constantly admitted from the intake of the machine to said pressure surface or surfaces and in this instance such small amount of pressure is admitted through the aperture h in the end o of the main valve. The outward movement of the main valve is preferably limited by means of the stop j. 110

An exhaust to atmosphere is provided from the rear pressure surface or surfaces of the main valve through the exhaust aperture *h* and an auxiliary pilot valve *o* is provided for varying said exhaust. The pilot valve is preferably in the form of a hollow cylinder closed at its inner end *p* and adapted to slide within a casing *q* open at both ends and held in position as by means of the cap *r* having the ports *s*. The pilot valve *o* is at all times subjected to the pressure of the spring *t* forcing the valve in a direction adapted to produce the maximum exhaust opening from the rear pressure surface or surfaces of the main valve *b*. In this instance the pilot valve *o* is provided with the apertures *u* in its walls arranged at an angle to the longitudinal axis of the valve so that as the pilot valve moves inwardly into the position indicated in Figure 3 for instance, motive fluid may exhaust from the space behind the main valve *b* through the exhaust port *h*, into the casing *q* through the port *v* and through the plurality of apertures *u* to the inside of the pilot valve and thence to atmosphere.

The end *p* of the pilot valve is at all times subjected to the pressure in the motor through the port *w*, tending to force the pilot valve in the opposite direction to reduce the communication between the rear pressure surface or surfaces of the main valve *b* and the atmosphere, because as the pilot valve *o* moves outwardly in the casing *q*, more or less of the apertures *u* are cut off or closed.

In the operation of the apparatus, let it be assumed that the drill steel *D* for any cause, encounters increased resistance to rotation. A drag is thus put upon the motor causing the same to run slower, which increases the pressure on the intake side within the motor casing *G*. The pilot valve *o* then moves outwardly, reducing the communication from the rear end of the main valve *b* to the atmosphere, which builds up the pressure behind the rear end of the said main valve *b* and opens it further, still further increasing the pressure in the motor, and causing it to exert greater power for rotating the drill steel. This condition continues until the drill steel works itself free, in which case, the motor will momentarily race, and relieve itself of the pressure, dropping the pressure on the intake side in the motor casing, so that the pilot valve will then return to substantially its original position and the main valve will return to normal position. This cycle of operations will be carried out whenever the conditions of the work require the automatic regulation.

I claim:

1. In a fluid operated percussive tool, the combination of a fluid operated rotation motor, a valve casing having a supply passage

leading to the motor, a valve adapted to automatically vary the opening through said passage inversely as the line pressure so as to maintain a substantially constant quantity of flow to the motor with varying line pressure, and adapted to automatically vary the said opening inversely with the speed of the motor so as to maintain approximately constant motor speed under varying loads, said valve being actuated in one direction by line pressure, and in the opposite direction by spring pressure and line pressure reduced inversely as the speed of the motor.

2. In a fluid operated percussive tool, the combination of a fluid operated rotation motor, a valve casing having a supply passage leading to the motor, a valve adapted to automatically vary the opening through said passage inversely as the line pressure so as to maintain a substantially constant quantity of flow to the motor with varying line pressure, and adapted to automatically vary the said opening inversely with the speed of the motor so as to maintain approximately constant motor speed under varying loads, said valve being actuated in one direction by line pressure, and in the opposite direction by spring pressure, and line pressure entering behind the valve through a restricted port and passing to atmosphere through a second restricted port.

3. In a fluid operated percussive tool, the combination of a fluid operated rotation motor, a valve casing having a supply passage leading to the motor, a valve adapted to automatically vary the opening through said passage inversely as the line pressure so as to maintain a substantially constant quantity of flow to the motor with varying line pressure, and adapted to automatically vary the said opening inversely with the speed of the motor so as to maintain approximately constant motor speed under varying loads, said valve being actuated in one direction by line pressure, and in the opposite direction by spring pressure, and line pressure entering behind the valve through a restricted port and passing to atmosphere through a second restricted port, and a pilot valve in said valve casing controlled by the motor pressure, governing the opening of said second restrictive port.

4. In a fluid operated percussive tool, the combination of a fluid operated rotation motor, a valve casing having a supply passage leading to the motor, a valve adapted to automatically vary the opening through said passage inversely as the line pressure so as to maintain a substantially constant quantity of flow to the motor with varying line pressure, and adapted to automatically vary the said opening inversely with the speed of the motor so as to maintain approximately constant motor speed under varying loads, said valve being constantly

subjected to spring pressure tending to move the valve in a direction to increase the opening through said passage, one pressure surface of said valve being constantly subjected to the pressure of the incoming motive fluid tending to move the valve in the opposite direction to reduce the opening through said passage, another opposing pressure surface of the valve being subjected to the varying pressure due to a relatively small amount of fluid constantly admitted through a restricted port from the intake of the machine behind said other pressure surface, means for exhausting the space behind said other opposing pressure surface of the valve through a second restricted port to atmosphere, and a spring pressed auxiliary pilot valve in said valve casing automatically controlled by the pressure in the motor, governing the opening of said second restricted port.

5. In a fluid operated percussive tool, the combination of a fluid operated rotation motor, a valve casing having a supply passage leading to the motor, a valve adapted to automatically vary the opening through said passage inversely as the line pressure so as to maintain a substantially constant quantity of flow to the motor with varying line pressure, and adapted to automatically vary the said opening inversely with the speed of the motor so as to maintain approximately constant motor speed under varying loads, said valve being constantly subjected to spring pressure tending to increase the opening through said passage, one pressure surface of said valve being constantly subjected to the pressure of the incoming motive fluid tending to move the valve in a direction to reduce the opening through said passage, another opposing pressure surface of the valve being subjected to the varying pressure due to a relatively small amount of fluid constantly admitted from the intake of the machine behind said other pressure surface through a restricted port in the front end of the valve, means for exhausting the space behind said other opposing pressure surface of the valve through a second restricted port to the atmosphere, and a spring pressed auxiliary pilot valve in said valve casing automatically controlled by the pressure in the motor, governing the opening of said second restricted port.

6. In a fluid operated percussive tool, the combination of a fluid operated rotation motor, a valve casing having a supply passage leading to the motor, a valve adapted to automatically vary the opening through said passage inversely as the line pressure so as to maintain a substantially constant quantity of flow to the motor with varying line pressure, and adapted to automatically vary the said opening inversely with the

speed of the motor so as to maintain approximately constant motor speed under varying loads, said valve being constantly subjected to spring pressure tending to move the valve in a direction to increase the opening through said passage, one pressure surface of said valve being constantly subjected to the pressure of the incoming motive fluid tending to move the valve in the opposite direction to reduce the opening through said passage, another opposing surface of the valve being subjected to the varying pressure due to a relatively small amount of fluid constantly admitted through a restricted port from the intake of the machine behind said other pressure surface, means for exhausting the space behind said other opposing pressure surface of the valve through a second restricted port to atmosphere, and an auxiliary pilot valve governing the opening of said second restricted port.

7. In a fluid operated percussive tool, the combination of a fluid operated rotation motor, a valve casing having a supply passage leading to the motor, a valve adapted to automatically vary the opening through said passage inversely as the line pressure so as to maintain a substantially constant quantity of flow to the motor with varying line pressure, and adapted to automatically vary the said opening inversely with the speed of the motor so as to maintain approximately constant motor speed under varying loads, said valve being subjected to spring pressure tending to move the valve in a direction to increase the opening through said passage, one pressure surface of said valve being continually subjected to the pressure of the incoming motive fluid tending to move the valve in the opposite direction to reduce the opening through said passage, another opposing pressure surface of the valve being subjected to the varying pressure due to a relatively small amount of fluid constantly admitted through a restricted port from the intake of the machine behind said other pressure surface, means for exhausting the space behind said other opposing pressure surface of the valve through a second restricted port to atmosphere, an auxiliary pilot valve in the valve casing governing the opening of said second restricted port, resilient means tending to force said pilot valve in a direction to produce the maximum exhaust opening through the said second restricted port to the atmosphere, said pilot valve also being at all times subjected to the pressure in the motor, tending to force the pilot valve in the opposite direction to reduce the opening through said second restricted port to the atmosphere.

8. In a fluid operated percussive tool, the combination of a fluid operated rotation motor, a valve casing having a supply passage

leading to the motor, a valve adapted to automatically vary the opening through said passage inversely as the line pressure so as to maintain a substantially constant quantity 5 of flow to the motor with varying line pressure, and adapted to automatically vary the said opening inversely with the speed of the motor so as to maintain approximately constant motor speed under varying loads, said 10 valve being constantly subjected to spring pressure tending to move the valve in a direction to increase the opening through said passage, a front pressure surface of said valve being constantly subjected to the pressure of the incoming motive fluid tending to move the valve in the opposite direction to reduce the opening through said passage, a rear pressure surface of the valve being subjected to the varying pressure due to a relatively small amount of fluid constantly admitted through a restricted port from the 15 intake of the machine to said rear pressure

surface, the valve also being provided with an exhaust from the rear pressure surface through a second restricted opening to the atmosphere, and an auxiliary pilot valve governing the opening of said second restricted port, one portion of said pilot valve being at all times subjected to spring pressure forcing it in a direction adapted to produce the maximum opening through the second restricted port from the rear pressure surface of the first named valve to the atmosphere, the opposite end of said pilot valve being at all times subjected to the pressure in the motor, tending to force the pilot valve in a direction to reduce the opening through said second restricted port from the rear pressure surface of the first named valve to the atmosphere. 20 25 30 35 40

In testimony whereof I have signed this specification.

FRED M. SLATER.
